UNITED STATES PATENT OFFICE

151,224

DESIGN FOR A TEXTILE FABRIC OR SIMILAR ARTICLE

Samuel A. Dix, New York, N. Y., assignor to Bartmann & Bixer, Inc., New York, N. Y., a corporation of New York

Application October 3, 1947, Serial No. 141,722

Term of patent 14 years

(Cl. D92—1)

To all whom it may concern:

Be it known that I, Samuel A. Dix, a citizen of the United States, resident of the city of New York, in the county of New York, State of New York, have invented a new, original, and ornamental Design for a Textile Fabric or Similar Article, of which the following is a specification, reference being had to the accompanying drawing, forming part thereof.

In the drawing, the figure is a plan view of a textile fabric showing my new design, a design unit of which is outlined by dotted lines. Said unit repeats over the textile fabric as indicated.

I claim:

The ornamental design for a textile fabric or similar article, substantially as shown and described.

SAMUEL A. DIX,
